MOLDING MACHINE

Louis D. Plassmeyer, Zelienople, Pa., assignor
to Herman Pneumatic Machine Company,
Zelienople, Pa., a corporation of Pennsyl-
vania

Application March 7, 1938, Serial No. 194,312

11 Claims. (Cl. 22—26)

My invention is an improvement in molding machines for foundry practice in which the sand, pattern and flask are subjected to a vibrating or jarring agitation, followed by a final compression of the sand. Such machines of different constructions are now in somewhat general use, of the types disclosed in prior patents of Ringle No. 1,054,315 and 1,803,406.

In general, such machines are provided with a reciprocably operating flask-supporting table actuated by a plunger or the like for limited up and down movement, and a resisting squeezing head. Also means for imparting additional supplemental travel to the plunger table for final compression of the molding sand against said head.

Heretofore the squeezing head and its operating parts have been of constructions involving a considerable degree of manual operation and adjustment and lacking in satisfactory balance and weight compensation.

The present invention is designed to improve the machine in such features. It comprises a squeeze head so mounted and balanced as to be easily located and firmly held in either operative or inoperative relation to the plunger table, with a minimum of effort and firm and secure holding efficiency.

Referring to the drawings showing one preferred construction:

Fig. 1 is a view of the machine in side elevation showing the squeeze head in inoperative elevated position;

Fig. 2 is a similar view showing the squeeze head lowered for operation;

Fig. 3 is a plan view of Fig. 2;

Fig. 4 is a partial rear view of Fig. 2 showing the cantilever extension of the squeeze head, latch mechanism, and balancing springs;

Fig. 5 is a detail sectional view on the line V—V of Fig. 2, from the rear;

Fig. 6 is a detail sectional view on the line VI—VI of Fig. 5;

Fig. 7 is a similar view on the line VII—VII of Fig. 5;

Fig. 8 is a detail view in part section elevation showing a supplemental filler block for the squeeze head;

Figs. 9 and 10 are similar views in side and end elevation respectively showing a modified construction of filler block.

The main frame or base 2 of the machine is mounted on a supporting stationary foundation, or on wheels 3 if preferred for portable use. At the front of the machine is a cylinder 4 of suitable construction for reception and vertical limited

oscillation or jarring of a flask-supporting plunger 5 having a terminal table or flask and pattern supporting plate 6, of well known construction.

Any suitable means, as an additional plunger, is ordinarily provided for final squeezing elevation of the flask 7, shown in dotted lines, upwardly towards the squeeze head 8, with an intervening follow board 9, as in Patent 1,054,314, supra.

The squeeze head or rammer 8 forms the outer front portion of a cantilever arm A which is pivotally mounted by cheek bearings 10 about midway on the cross pin or trunnion shaft 11. Lever A extends therebeyond for connection by its rear terminal with the locking and guiding means, hereinafter described.

Extending upwardly from base 2 is a standard or post 12, through the upper end of which extends the journaling trunnion shaft 11 for the lever arm A. Shaft 11 is maintained stationary against rotation by any suitable means, as a pin 20 or screw 13 and is provided at each end with a spring resisting disk or the like, 14 and 15 respectively. The disks are secured to the ends of shaft 11 by suitable means, as bolts 16, and are fixedly held against rotation as immovable parts of the shaft, by positive connecting means, as pins 17, or equivalent.

In lowering the squeeze head 8 from the inoperative position of Fig. 1 to the resisting or sand compressing position of Fig. 2, it is desirable to assist the forward pull of the operator to a position approximating say one half of its movement, and to thereafter resist increasing gravitation as the head 8 approaches its lowered operative position. A further important incident is to firmly lock the head against upward pressure when so positioned.

A further object is to assist the initial raising of the head after the squeezing operation and to store up energy during the latter portion of the back throw for such subsequent forward pull, prior to the next squeezing operation.

To these ends I utilize a pair of coiled springs 18 surrounding the shaft 11 and co-operating means adapted to exert torsionally applied pressure thereon to assist both raising and lowering movements, as above noted.

To effect such objects each disk 14 and 15 is provided with a fixed lug or abutment 19 engageable with the outer terminal of spring 18, and similar abutments 20, movable with the lever A, engage the other or inner spring terminals. It may be assumed that in the midway position of the lever the resisting action of both springs is substantially equal, or nil.

Abutment 20 is preferably mounted on a separate adjusting plate 21 journalled around each end portion of trunnion 11 and held to lever A by a set screw 22 extending through annular slot 23.

By such construction, the plate 21 and its abutment 20 may be annularly adjusted to regulate or modify the torsional resistance of either spring 18 to assist in determining the most effective spring action in operating the lever in either direction for most efficient counterbalancing.

In order to effect proper upward tilting of the lever A and its head 8 and also for positive locking of same when lowered, the machine is provided with a pair of spaced apart side plates 24.

Each of such plates has an arcuate eccentric slot 25 terminating in an outwardly off-set shoul dered locking socket 26, each oppositely registering with the other.

Pivoted on a cross pin 27 at the rear end of lever A is a pair of lever arms 28 having at their lower ends a cross pin or latch 29, the terminals of which are adapted to seat into sockets 26 and against shoulder *a* thereof, to firmly resist upward pressure on head 8, as in Fig. 2. Arms 28 are connected at their upper ends by cross pin 30 which is engaged by the end of connecting bar or link 31 of operating lever 32. Said lever is pivoted at 33 to a stud 34 at the inner upper portion of the head 8, and at 35 with the other end of bar 31, and has a handle 36 for grasping, positioned at the front above the head.

By such means, assuming the ramming head 8 to be in the lowered position of Fig. 2 upon completion of compression, lifting of lever 32 by handle 36 will effect disengagement of pin 29 from shoulder *a*, as shown by dotted lines. Such operation thrusts pin 29 inwardly in register with slots 25 which, acting as cams, cause the locking and unlocking mechanism to assume the position shown in Fig. 1 when the lever A is thus thrust upwardly and backwardly. Head 8, as elevated by lever A, is initially assisted by the torsional reaction of spring 18 (left side of Fig. 5) for say half of its rising travel, after which the opposite spring 18 is torsionally energized by the opposite abutment 20.

The reacting energy thus developed, while insufficient to itself effect reverse movement of lever A, greatly assists and reduces the otherwise necessary manual power in again bringing the head 8 downwardly towards the flask. For the last portion of such movement the gravitating tendency of the comparatively heavier head steadily increases and is largely but not entirely resisted by the next torsionally developed resistance of the opposite spring. Such resistance of course is then available in the form of stored power, and is of material assistance in the next elevation of the head, as described.

The head 8, as is apparent, thus assumes a uniformly fixed lowered position with relation to flasks of substantially uniform height, and when raised, is thrown backwardly entirely beyond and out of interference with subsequent flask removal or replacement. Wherever flasks of less or suitable height are utilized, a filler block 37 of suitable depth may be secured to the head 8 in any available manner, as by a central bolt 38 extending upwardly through a boss 39 in the middle of the head, as in Fig. 8.

Any number of such filler blocks may be utilized, of such depth dimensions as to provide for compensating pressing face levels, to suit conditions arising in use.

I show in Figs. 9 and 10 a modified construction in which the filler block 37a is made comparatively shallow and is provided with means for locating the block at variable distances below the main head 8. These consist of side arms 40 extending upwardly from the block at each side of the head having a plurality of bolt holes 41 for connection by transverse bolts 42 through the flanges thereof.

The central bolt 38a in such case is elongated as shown for adjustment of the block, facilitating accurate placement and tightening of bolts 42 in locating the block 37a. By such construction a single filler block may be used for different compression resistance levels when variable height flasks are used.

The construction and operation of the machine will be readily understood and appreciated from the foregoing description.

In either raising or lowering the springs 18 tend to counteract gravitation in all positions of the head, and by alternating storage of effective power, greatly assist manual operation in both directions. In lowering from erected position of the main lever the handle 36 is located closely toward the forward upper edge of head 8. When in final operating position, due to cam action of slots 25 elevating handle 36 to dotted line position of Fig. 2, the handle is raised sufficiently to allow by downward pressure for positive thrusting of the locking or latch pin in socket 26 and against shoulder *a*, for positive holding of the head against upwardly exerted sand-compressing forces, without displacement. This is because of the positive interlock effected and the final vertical position of the arms 28. In either lowering or raising of the head, handle 36 moves in general conformity and approximate close relation to the front of head 8.

It will be understood that the proportions of the machine and its parts may be varied or changed to suit different conditions of foundry practice or use of the invention. Also that it may be altered in detail construction by the skilled mechanic or builder, within the scope of the following claims.

I claim:

1. In a molding machine as described provided with a flask, a lever having at one end a pressure resisting head engageable with the flask, a movement arresting latch pivoted at the other end of the lever, an intervening pivot mounting for the lever, a fixed holding bearing for the latch, engaging and disengaging means for the latch mounted on the lever having a grasping handle adjacent the head, and means coincident with the pivot mounting adapted to generate balancing resistance to the lever opposing its tilting movement in either direction.

2. In a molding machine as described provided with a flask, a lever having at one end a pressure resisting head engageable with the flask, a movement arresting latch at the other end, an intervening pivot mounting, a holding bearing for the latch, engaging and disengaging means for the latch, and means coincident with the pivot mounting adapted to generate balancing resistance against movement of the lever in either direction.

3. In combination with a molding machine 70 flask, a pivoted lever having at opposite end portions a pressure resisting head engageable with the flask and a movable latch, manually operated means on the lever for moving the latch having a grasping handle adjacent the head, a fulcrum 75

bearing for the lever, and supporting and guiding means for the latch.

4. In combination with a molding machine flask, a lever having at opposite end portions a pressure resisting head and a movable latch, an intervening fulcrum bearing for the lever, means coincident with the fulcrum bearing adapted to generate balancing resistance against movement of the lever in either direction, and fixed supporting and guiding means for the latch.

5. In combination with the main lever of a flask supporting molding machine having at one end a pressure resisting head engageable with the flask, a holding latch pivoted on the opposite end 15 of the lever, and said latch having a lower bearing-engaging terminal and an upper connecting terminal, an actuating lever pivoted on the main lever having a handle adjacent the head and means connecting the actuating lever with said 20 upper connecting terminal of the latch.

6. In a molding machine provided with a flask support and vertically operable actuating means therefor, a lever-supporting journal bearing, a pair of side plates having guiding cam slots terminating in off-set latch supporting bearings, a lever mounted in the journal bearing having a pressure resisting head opposing the flask support and a latch, and manually operated means for actuating the latch.

7. In a molding machine provided with a flask support and vertically operable actuating means therefor, a lever-supporting journal bearing, a pair of side plates having guiding cam slots terminating in off-set latch supporting bearings, a lever mounted on the journal bearing having a pressure resisting head opposing the flask support and a latch, manually operated means for actuating the latch, a torsional spring at each opposite side of the lever bearing, and cooperating adjustable 35 abutments on the lever engageable therewith.

8. In a molding machine provided with a flask support and vertically operable actuating means

therefor, a lever-supporting journal bearing, a pair of side plates having guiding cam slots terminating in off-set latch supporting bearings, a lever mounted on the journal bearing having a pressure resisting head opposing the flask support and a latch, and latch actuating means mounted on the lever provided with a handle.

9. In combination with the tilting lever of a molding machine as described having a flask-engaging pressure head, a supporting shaft for 10 the lever, and a fixed trunnion therefor, a torsion spring on each end of the trunnion having a free inner terminal, and a rotatable abutment at each side of the lever engageable with one or the other of said terminals when the lever is oppositely 15 tilted.

10. In combination with the tilting lever of a molding machine as described having a flask-engaging pressure head, a supporting shaft for 20 the lever, and a fixed trunnion therefor having a 25 limiting abutment at each outer end, a torsion spring surrounding each outer end of the shaft engageable by its outer terminal with one of said abutments, a plate at each side of the lever adjustable with relation to the trunnion, and an abutment on each plate engageable with the inner 30 terminal of one of said springs.

11. In combination with the tilting lever of a molding machine as described having a flask-engaging pressure head, and a supporting stand- 30 ard having a fixedly mounted trunnion shaft for the lever extending therethrough on which the lever is mounted by bifurcated bearing portions, a spiral spring surrounding each end portion of the trunnion shaft, a disk fixedly secured to each 35 end of the shaft having a spring engaging abutment, a plate journaled on the shaft at each side of the lever having a spring engaging abutment and a slot, and a securing bolt for each plate extending through the slot into the face of the 40 lever.

LOUIS D. PLASSMEYER.
